CLAIM

The ornamental design for a telecommunications connector, as shown and described.

DESCRIPTION

FIG. 1 is a right side perspective view of a telecommunications connector, showing my new design;

FIG. 2 is a front elevation view thereof;

FIG. 3 is a rear elevation view thereof;

FIG. 4 is a top plan view thereof;

FIG. 5 is a bottom plan view thereof; and

FIG. 6 is a right side elevation view thereof, the left side elevation view being substantially a mirror image thereof.

FIG. 1

FIG. 4

FIG. 3

FIG. 5

FIG. 2

FIG. 6
